GRADER

Filed Oct. 6, 1925

By *Swift* Attorney

UNITED STATES PATENT OFFICE

WILLIAM B. QUILLE, OF COTTONWOOD, CALIFORNIA

GRADER

Application filed October 6, 1925. Serial No. 60,791.

The invention relates to graders, particularly of the type shown in Patent No. 1,510,958, issued to William B. Quillen, October 7th, 1924, and has for its object to provide a U-shaped bracket through which the arcuate member carried by the pivoted scraper blade moves, and which U-shaped bracket is provided with arms engaging the upper side of the scraper beam, and held in close engagement with the scraper beam by means of U-shaped bolts, the arms of which extend through plates disposed on the upper side of the bracket arms, thereby positively holding the bracket in place on the upper side of the beam.

A further object is to provide a sliding bolt extending through an upwardly extending arm of one of the arms of the bracket and through registering apertures in the U-shaped member, and an aperture in the segmentally shaped member, and which latching bolt is maintained in operative position by means of a coiled spring. The latching bolt forms means for allowing the grader blade to be easily and quickly adjusted to any desired position, and held in adjusted position.

A further object is to dispose the latching device and the apertured segmentally shaped member above the beam where they will not come into engagement with dirt, vines or other material during a scraping operation.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a top plan view of the grader.

Figure 2 is a side elevation of the grader.

Figure 3 is a perspective view of the latching device, and bracket.

Referring to the drawing, the numeral 1 designates the beam of the grader, the rear end of which is provided with a downwardly extending arm 2, to which is pivotally connected at 3 a ground scraping blade 4. Ex-

tending downwardly from the beam 1 adjacent its forward end is an arm 5 which terminates in a horizontally disposed portion 6, adapted to slide over the ground forwardly of the scraping blade 4 for supporting the forward end of the beam 1 at a substantial uniform distance from the ground during the scraping operation of the blade 4. It will be noted the blade 4 can be moved to various positions in a horizontal plane for discharging the dirt collected thereby to either side of the grader during the scraping operation. Blade 4 is provided with a substantially horizontally disposed segmentally shaped guide bar 7 having a plurality of spaced apertures 8 therein, and with which guide bar latching means cooperates for holding the scraper blade in various adjusted positions in a horizontal plane. The bar 7 is disposed above the beam 1 where it will not engage material during a scraping operation.

The latching device comprises a U-shaped bracket 9 above the beam 1, the arms 10 of which extend downwardly and terminate in oppositely extending arms 11 which closely engage the upper side of the beam 1, and are held in close binding engagement with the beam 1 by means of U-bolts 12, which arch the underside of the beam and extend through the plates 13 and 14 disposed on the upper sides of the arms 11, and one of which plates has secured thereto the handle members 14^a and the brace rods 15, therefore it will be seen that it is not necessary to drill the beam 1, and the handle members and braces may be assembled on the plate 14 and placed in position and the U-shaped bolts 12 placed under the beam 1 and through the apertures 15^a of the plates 13 and 14, and the handles attached to the beam as well as the bracket by means of the bolts. It will also be seen that the U-shaped bolt 12 at the forward end of the plate forms means for securing the brace rods 15 to the plate 14, therefore they perform a double function. The rear end of one of the arms 11 is provided with an upwardly extending arm 16, and in which arm, and the arms 10 a slideable latch bolt 19 is mounted, the outer end of which is provided with a loop 20 adapted to be grasped by the

100

operator for moving the sliding bolt 19 outwardly against the action of the coiled spring 21 which is interposed between the arm 16 and the pin 22 of the bolt, when it is desired 5 to adjust the blade 4 to a different position. The sliding bolt 19 extends through registering apertures 23 of the arms 10 of the bracket and through one of the apertures 8 in the segmentally shaped guide bar 7, and when in 10 locked position positively holds the scraping blade 4 against pivotal movement during the scraping operation.

From the above it will be seen that a positive latching device is provided for a segmentally shaped brace bar of a grader blade, which latching device is provided in connection therewith with a U-shaped guide bracket for the brace bar, and the same securing bolts which hold the latching device also holds 15 the handle carrying plate disposed on the upper side of the beam, and the beam is not weakened by drilling holes for the bolts. It will be seen also that the segmentally shaped bar 7 and the latching device are disposed 20 above the beam 1 and scraper 4 therefore they will not come into engagement with material 25 being scraped by the blade 4.

The invention having been set forth what is claimed as new and useful is:—

- 30 1. A grader comprising a beam, a pivoted blade carried thereby, a segmentally shaped apertured guide and brace bar carried by said blade and disposed above the beam, a latching device for said brace bar, said device comprising a U-shaped bracket above the beam through which the segmentally shaped brace bar extends, outwardly extending arms carried by the U-shaped bracket and engaging the upper side of the beam, U-bolts arching 35 the under side of the beam for holding said arms in close binding engagement with the upper side of the beam, transversely disposed plates engaging the upper sides of the bracket arms and through which the bolts extend, one 40 of said arms being provided with an upwardly extending member spaced from the U-shaped bracket and disposed in a recess in one of the plates, a sliding bolt extending through the upwardly extending member and registering apertures in the U-shaped bracket, a 45 stop carried by said sliding bolt and a coiled spring surrounding the sliding bolt and interposed between the stop and the upwardly extending member.
- 50 55 2. A grader comprising a beam, a pivoted scraper carried by said beam, a segmentally shaped apertured brace bar carried by said scraper and disposed above the beam, a bracket engaging the upper side of the beam, latching means carried by said bracket and cooperating with the brace member for holding the same in various adjusted positions, a plate disposed on the upper side of the bracket, handle members carried by said plate and entirely 60 supported thereby, brace rods connecting said 65

plate and the handle members, U-shaped bolts arching the underside of the beam and extending through the plate, one of said U-shaped bolts having its arms extending through the brace members carried by the plate and two 70 of said bolts having their arms extending through the handles.

In testimony whereof I affix my signature.

WILLIAM B. QUILLEN.
